UNITED STATES PATENT OFFICE.

HENRY B. KEIPER, OF LANCASTER, PENNSYLVANIA.

DESIGN FOR A COVER FOR BOOKS OR CATALOGUES.

No. 38,329.

Specification for Design.

Patented Nov. 27, 1906.

Application filed October 15, 1906. Serial No. 339,117. Term of patent 14 years.

To all whom it may concern:

Be it known that I, HENRY B. KEIPER, a citizen of the United States, residing at Lancaster, in the county of Lancaster and State of Pennsylvania, have invented a new, original, and ornamental Design for Covers for Books or Catalogues, of which the following is a specification, reference being had to the accompanying drawing, forming part thereof.

The figure is a front view of a cover for a book or catalogue, showing my new design.

I claim—

The ornamental design for a cover for a book or catalogue, substantially as shown.

HENRY B. KEIPER.
